UNITED STATES PATENT OFFICE.

NELSON HOLMES, OF YPSILANTI, MICHIGAN, ASSIGNOR TO AUGUSTUS B. PROUTY, OF WORCESTER, MASSACHUSETTS.

IMPROVEMENT IN LATCHES.

Specification forming part of Letters Patent No. 222,907, dated December 23, 1879; application filed February 18, 1879.

To all whom it may concern:

Be it known that I, NELSON HOLMES, of Ypsilanti, in the county of Washtenaw and State of Michigan, have invented certain new and useful Improvements in Door-Knobs and Latch-Actuating Mechanism; and I do hereby declare the following to be a full, clear, and exact description of the invention, such as will enable others skilled in the art to which it pertains to make and use it, reference being had to the accompanying drawings, which form part of this specification.

My invention relates to an improvement in door-knobs and latch-actuating mechanism, the object being to provide a door-knob with simple and effective mechanism, whereby the latch can be readily retracted without turning the knob, and thus enable the latter to be firmly secured to the door-casing in any desired manner; and to this end my invention consists, first, in the combination, with a spring-pressed latch-bolt, of a knob the rose of which is rigidly secured to the door-casing, the shank of the knob being hollow and provided with a reciprocating push-rod having one arm of a bell-crank lever pivoted to the end thereof, the long arm of said bell-crank lever being arranged and adapted to engage with the latch-bolt, whereby, a reciprocatory movement being imparted to the thumb-piece, the latch will be retracted and unlocked.

My invention further consists in the several details of construction and combinations of parts, as will hereinafter be explained, and pointed out in the claims.

In the accompanying drawings, Figure 1 is a vertical section of my improved door-knob, illustrating the position of the parts when the door is closed; and Fig. 2 is a similar view, showing the latch-bolt retracted.

A represents the rose, which is, preferably, provided with wings *a*, two or more, for the secure attachment of the same by screws to the door-casing. Instead of providing the rose with wings or lugs, it may be formed with an outwardly-projecting flange suitably perforated for the insertion of screws for the secure attachment of the rose to the casing or other fixed support.

To the rose A is secured one end of a tubular stem, B, which is either swaged firmly to the rose, or it may be cast solid therewith. The outer end of stem B is provided with lugs or fins *b*, which are received in corresponding grooves in the knob C, whereby the latter is prevented from turning on the end of the stem.

The knob is prevented from being pulled off from the stem B by means of a collar, *c*, which is swaged upon the outer end of the hollow stem. Surrounding the hollow stem B is a sleeve, D, one end of which rests against the rose, while the other end is provided with a collar, *d*, which rests against the inner surface of the knob and prevents the knob from being forced toward the rose.

From the foregoing it will be observed that the knob C is held from endwise movement on the hollow stem by means of the collars *c* and *d*, and held against rotary movement by means of the lugs or fins *b*. The outer face of knob C is recessed for the reception of the thumb-piece E, the latter being, preferably, constructed cylindrical in form, whereby it is guided and retained in place within the recess F in the knob.

G is a push-rod, one end of which is secured to thumb-piece E, or formed solid therewith, while the other end is slotted at *e* for the reception of the short end of the bell-crank lever H, and is pivoted thereto by the pin *h*. Bell-crank lever H is pivoted to the lugs I on the inner face of the rose A. The long arm J of bell-crank lever engages in a slot, K, formed in one end of a latch-bolt, which is pressed forward by a spring arranged in any suitable manner.

As my improvement is adapted to be applied to a great many different constructions of latches, I do not limit myself to its application to the particular form of latch shown in the accompanying drawings.

By pressing on the thumb-piece the push-rod is forced inwardly, and operates to force the long arm of the bell-crank lever in a lateral direction and move the latch-bolt in opposition to the force of its spring.

Instead of employing a spring in connection with the latch-bolt, a spring may be arranged

within the recess in the rose to force the thumb-piece outwardly.

When the hollow stem is formed solid with the rose the sleeve is first placed over the stem. The knob is then forced onto the outer end of the stem and forced against the collar on the outer end of the sleeve. A collar is then placed around the end of the hollow stem, which projects within the recess in the knob, and the collar is then firmly swaged to the stem.

When the hollow stem is made independent of the rose, the collar on the stem may be swaged thereon or cast solid therewith, and the stem, having been inserted through the knob with its collar resting on the bottom of the recess therein, the outer sleeve is then applied, and the inner end of the hollow stem then swaged fast to the rose.

A door-knob and latch-actuating mechanism constructed in accordance with my invention is of simple and durable construction and of small initial cost. The knob can be securely attached to the door-casing or other fixed support, and is not liable to be detached therefrom, as it is made rigid with the rose. The latch is operated by imparting a slight movement to the thumb-piece by reason of the different lengths of the arms of the bell-crank lever; and as the thumb-piece is protected against displacement, (it being seated within the recessed knob,) the parts are not liable to become disarranged or impaired by constant use. By pivoting the bell-crank lever within the recess of the rose it is entirely concealed from view and completely protected from the weather, thus preventing the joints from becoming rusty and inoperative. The end of the short arm of the bell-crank lever is brought in line with the center of the shank of the knob, so that the push-rod may operate in a direct line in actuating the bell-crank lever.

I am aware that it is not new to employ a bell-crank lever in connection with a lock or latch, and hence I make no broad claim to such element irrespective of its position and relative arrangement of parts with which it operates.

The knob may be made of porcelain, metal, or any other material desired, and the rose may be made of cast metal, or struck up from brass or other sheet metal.

It is evident that many slight changes in the construction and arrangement of parts may be resorted to without departing from the spirit of my invention, and hence I do not limit myself to the exact construction shown and described; but,

Having fully described my invention, what I claim as new, and desire to secure by Letters Patent, is—

1. The combination, with the rose-plate having a bell-crank lever pivoted within the recess formed therein, the long arm of said lever projecting from the recessed rose and adapted to engage with a latch-bolt, of a push-rod located within the shank of the knob and pivoted at one end to the short arm of the bell-crank lever, and a thumb-piece attached to the outer end of the push-rod, substantially as set forth.

2. The combination, with a rose-plate having one end of a hollow stem attached thereto, of a sleeve surrounding said hollow stem, and a knob secured to the outer end of the hollow stem and prevented from rotary displacement therein by means of fins or lugs on the end of said stem, substantially as set forth.

3. The combination, with a rose-plate and a hollow stem attached thereto, of a sleeve surrounding said stem, said sleeve provided with a collar to prevent the knob moving toward the rose-plate, and a collar on the hollow stem which prevents the knob from moving in the opposite direction, substantially as set forth.

4. The combination, with a rose-plate having a bell-crank lever pivoted within its recessed face, the long arm of said bell-crank lever projecting from the recessed rose and adapted to engage with a latch-bolt, of a knob furnished with a hollow shank, a push-rod located within said hollow shank, one end of which is pivoted to one of the arms of the bell-crank lever, while the opposite end is furnished with a thumb-piece, which is located within a recess in the outer face of the knob, substantially as set forth.

5. The combination, with a recessed rose-plate, of a bell-crank lever pivoted therein, one end of said lever adapted to engage with a latch-bolt, and the other end connected with devices for imparting movement thereto, and thereby move the latch-bolt, substantially as set forth.

In testimony that I claim the foregoing I have hereunto set my hand this 11th day of February, 1879.

NELSON HOLMES.
